US00D575885S

(12) **United States Design Patent**
Adams et al.

(10) **Patent No.:** **US D575,885 S**
(45) **Date of Patent:** **** Aug. 26, 2008**

(54) **MELTING PLATE FOR A DECORATIVE CANDLEHOLDER**

(75) Inventors: **Mary Beth Adams**, Antioch, IL (US); **Janet Mrazek**, Racine, WI (US); **Chris A. Kubicek**, East Troy, WI (US); **Nathan R. Westphal**, Union Grove, WI (US)

(73) Assignee: **S. C. Johnson & Son, Inc.**, Racine, WI (US)

(**) Term: **14 Years**

(21) Appl. No.: **29/242,436**

(22) Filed: **Nov. 10, 2005**
